UNITED STATES PATENT OFFICE

2,009,006

OPHTHALMIC MOUNTING

Wayne S. Sears, Providence, R. I., assignor to
Universal Optical Corporation, Providence,
R. I., a corporation of Rhode Island

Application May 31, 1933, Serial No. 673,700

8 Claims. (Cl. 88—47)

This invention relates to an ophthalmic mounting and has for one of its objects the provision of means for mounting a strap upon a lens securely without the usual dangers of breaking the lens.

Another object of the invention is the provision of a construction which will apply sufficient pressure upon the lens by resilient action to hold the lens securely without danger of cracking or breaking the lens when set up to the desired tight position.

Another object of the invention is the provision of a construction which will apply sufficient pressure upon the retaining screw or bolt for securing the strap to the lens to prevent the bolt from becoming accidentally loosened.

Another object of the invention is the provision of a construction by which the hole through the lens strap and the hole through the lens need not be accurately positioned for securely holding the lens and strap together.

Another object of the invention is the provision of a resilient means in a strap which may be provided as a unit construction therewith for assembly.

Another object of the invention is the provision of a construction which will permit bending of the strap in adjustments by optometrists without destroying or rupturing the spring within the strap so as to render it incapable of performing its functions.

A further object of the invention is to provide a construction which will absorb shocks and thus prevent detrimental transmission of such to the glass lens.

With these and other objects in view, the invention consists of certain novel features of construction, as will be more fully described, and particularly pointed out in the appended claims.

In the accompanying drawing:

Fig. 1 is a perspective view of one of the lenses of a spectacle showing my improved construction as mounted both at the temple end piece and at the bridge connection.

Fig. 2 is a perspective view of the spring.

Fig. 3 is a perspective view of the strap.

Fig. 4 is a side elevation of the strap and spring mounted upon a fragmental portion of a lens the same being greatly enlarged.

Fig. 5 is a section on line 5—5 of Fig. 4.

Fig. 6 is a section similar to Fig. 5 of a modified form of spring.

Fig. 7 is a view similar to Fig. 5 of a different modified form of spring.

Fig. 8 is a section on line 8—8 of Fig. 7.

Fig. 9 is a view similar to Fig. 5 of a modified form of spring and modified form of strap.

Fig. 10 is a perspective view of one of the ears of the strap illustrating the recess shown in

Fig. 9.

Fig. 11 is a perspective view of a further modified form of spring, the ears being cut and slit along their peripheral edges.

Fig. 12 is a sectional view showing the riveting of the spring in position on the strap.

Fig. 13 is a view similar to Fig. 9 showing a further modification.

In the attaching of bridges, temples, nose pieces or the like parts of ophthalmic mountings to rimless lenses a so-called strap is usually provided having a base and spaced ears to extend over the opposite surface of the lens, the ears are perforated and the lens perforated through which there extends a securing bolt or screw to hold the parts assembled. In the setting up of this screw in the strap, if the same is turned in too tight the lenses are cracked, broken, or splintered around the opening, also if the hole in the lens is not the correct distance from the edge, then the openings through the ears of the strap do not properly align and if pressure is applied in securing these parts, the lens is apt to splinter or break or else it is not held tightly in position, and in order to avoid both of these undesirable results in a unit construction I have provided a lining member in the strap which is resilient and will not only serve to engage the edge of the lens to secure and tight connection with reference to aligning for the holes in the ears of the strap and the hole in the lens, but will also serve to absorb pressure ordinarily applied to the surface of the lens to hold the same in secure position and will enable a setting up of the securing bolt or screw to the desired amount whereby the strap is firmly and securely held in the lens without the breaking of the same as has been frequently experienced in practice, and the following is a detailed description of the present embodiment of this invention illustrating the preferred means by which these advantageous results may be accomplished.

With reference to the drawing I have illustrated a lens 15 which is shown generally circular although other polygonal shaped lenses such as an octagonal construction may be used where desired. The portion of the ophthalmic mounting, as shown, also illustrates a bridge 16 and a temple 17 hinged to an end piece 18. The bridge and temple are secured to the lens by means of a strap 19 which may be integral or soldered to the end of the bridge 16 or the end piece 18 as desired. This strap consists of a base 20, arcuate on its inner surface and of a curvature of less radius than the curvature of the lens which it is to receive. Ears 21 extend generally at right angles to this base 20 and are perforated as at 22, one of which perforations is threaded at 23 to receive a threaded securing bolt 24 therein.

A liner designated 25 is of a shape generally conforming to the shape of the strap and is posi-

tioned within the strap to contact with the lens at its edge as well as its surfaces. This liner is of spring material and so shaped as to be held under compression between the strap and the edge of the lens and also under compression between each of the ears and its adjacent surface of the lens.

The portion 26 of this spring liner is on the arc of a circle of less radius than the edge of the lens with which it is to contact so that it will engage the lens at its outer edges 27 while its portion, inwardly from the ends thereof, will engage the base of the strap preferably at the ends of the strap 28 to provide a more secure engagement therewith. This member 25 is provided with projecting portions 29 perforated as at 30 to receive the bolt 24 and in the showing in Fig. 2 tongues 31 are provided to extend inwardly and engage the opposite surfaces of the lens 15 and apply pressure thereagainst.

By this arrangement the strap is permitted of adjustment or relative movement with reference to the lens for the alignment of its holes 22 and 23 with the hole 32 in the lens while securing firm engagement therewith in several relative positions of adjustment and also as the bolt 24 is drawn in and the ears 21 of the strap tend to move toward each other, the resilient tongue 21 serves to resist this movement and when a firm engagement is had there is still room for more compression and the lens is thus held firmly without wobbling or swinging in either of two planes at right angles to each other thereby providing a rigid connection of the parts and a desirable secure engagement of the strap with the lens.

In some instances, instead of providing a single tongue as 31 I may provide a pair of tongues shown as 33 and 34 in Fig. 6. In other instances the ears of the spring may be cupped as at 35 shown in Figs. 7 and 8, with a sufficiently large opening as at 39 so that the contact 40 and 41 of each of these ears with the lenses will permit some movement inwardly and outwardly relative to the strap for the resilient action desired. In other cases the strap 41 may be recessed as at 42 to receive a single tongue 43 therein as shown in Fig. 9, or a double tongue 43 and 47 as shown in Fig. 13, by which arrangement the ears may be bent toward each other by a pair of pliers without the danger of unduly flexing the spring to seat it as might otherwise occur. In Fig. 11 I have shown a still further modified form of cupped ears 44 slit as at 45 to permit of resilient action and to provide a plurality of fingers 46 or tongues for engagement with the lens.

In some cases I may turn the edge of the spring liner inwardly about the opening 30 in the ears, as at 49 in Fig. 9, to enter the hole in the glass lens and better protect the edges of this hole from splintering.

The liner or spring may be secured to the strap through riveting or upsetting of one of the parts, such as rivet 48 over the liner, and thus a unit construction may be provided and a construction having the functions of securing the lens by engagement with its edge as well as by engagement with its opposite surfaces to prevent breaking and provide a secure connection which may be used at either the bridge or the temple side of the lens. Also this resilient liner or spring serves to absorb any shock received on the metal parts or bridge or temple and prevent their transmission to the lens in a force which will be detrimental thereto.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In an ophthalmic mounting for spectacles and eye-glasses, a member having a base portion with spaced ears extending in a generally right angular direction therefrom, and a spring liner extending along said base and along the opposite surfaces of said ears, the portion extending along said ears being provided with a plurality of fingers to engage said ears with resilient action. 5

2. In an ophthalmic mounting for spectacles and eye-glasses, a member having a base portion with spaced ears extending in a generally right angular direction therefrom, and a spring liner extending along said base and along the opposite surfaces of said ears, the portion extending along said ears being cupped and split at their edges for resilient action. 10

3. In an ophthalmic mounting for spectacles and eye-glasses, a member having a base portion with spaced ears extending in a generally right angular direction therefrom, provided with aligned pierced openings, and a spring liner extending along said base and along the opposite surfaces of said ears, the portion extending along said ears being cupped and provided with pierced openings to align therewith and with split edges for resilient action. 15

4. In an ophthalmic mounting for spectacles and eyeglasses, a member having a base portion with spaced ears extending in a generally right angular direction therefrom, and a spring liner extending along said base and along the opposite surfaces of said ears, the portion extending along one of said ears being provided with a finger to engage said ear with resilient action. 20

5. In an ophthalmic mounting for spectacles and eyeglasses, a member having a base portion with spaced ears extending in a generally right angular direction therefrom, and a spring liner extending along said base and along the opposite surfaces of said ears, each portion extending along said ears being provided with a finger to engage said ears with resilient action. 25

6. In an ophthalmic mounting for spectacles and eyeglasses, a member having a base with spaced ears, one of said ears having a recess therein and a liner extending along said ear with a finger held under compression extending into said recess. 30

7. In an ophthalmic mounting for spectacles and eyeglasses, a member having a base with spaced ears, each of said ears having a recess therein, a liner extending along said base and ears with fingers extending into the recesses in the ears. 35

8. In an ophthalmic mounting for spectacles and eyeglasses, a member having a base with spaced ears, a lens between said ears, a metallic spring liner secured to said member and extending along said lens and of an arc to engage the base and lens at spaced points and flexed to be held under compression and also extending along one of said ears and provided with a finger to be held under compression between said ear and the lens. 40

WAYNE S. SEARLES.
